United States Patent Office

Des. 182,410
Patented Apr. 1, 1958

182,410

TISSUE DISPENSER

Charles Gemora, Los Angeles, Calif.

Application May 7, 1956, Serial No. 41,362

Term of patent 14 years

(Cl. D4—3)

FIG. 1.

FIG. 2.

FIG. 3.

5

FIG. 5.

FIG. 4.

Fig. 1 is a perspective view of a tissue dispenser embodying my new design, the cover being shown in open position.

Fig. 2 is a top plan view of the same, the cover being shown in closed position.

Fig. 3 is a perspective view of the same taken from the rear corner.

Fig. 4 is a front view in elevation of the same.

Fig. 5 is a partial view in vertical section taken substantially upon the line 5—5 of Fig. 3 in the direction indicated.

I claim:

The ornamental design for a tissue dispenser, as shown.
